ERNEST CLAXTON, OF BERKELEY, CALIFORNIA.

SAFETY-STOP FOR ELEVATORS.

1,163,217.

Specification of Letters Patent.

Patented Dec. 7, 1915.

Application filed March 8, 1915. Serial No. 12,870.

To all whom it may concern:

Be it known that I, ERNEST CLAXTON, a citizen of the United States, residing at Berkeley, in the county of Alameda and State of California, have invented new and useful Improvements in Safety-Stops for Elevators, of which the following is a specification.

This invention relates to safety devices to be attached to or used in conjunction with elevator cars or cages for the purpose of impeding and gently arresting the fall of the car or cage in the event of accident, and to prevent injury to the occupants.

15 The invention consists of the parts and the combination and construction of parts as hereinafter more fully described and claimed, having reference to the accompanying drawings, in which—

20 Figure 1 is a vertical section through a car showing the application of the invention; the attachment being carried directly by the car. Fig. 2 is a similar view but showing the safety device as detached from 25 the car but arranged to be operated thereby in the event of accident.

Having reference to Fig. 1 A represents an elevator car or cage; 2 the elevator well or shaft with a body of water as 3 in the 30 bottom of the shaft. 4 is a downwardly projecting peripheral flange or skirting bell secured to the under-side of the elevator floor and intended as an air trap when submerged in the water. 5 is a conical or pyramidal deflector on the under-side of the 35 floor and inside the flange or bell 4 and adapted by reason of the churning motion of the water caused when the pyramid or cone strikes the water to co-act with the bell 40 and the contained air cushion in checking the descent of the car.

Where it is not desired to carry the weight of the arrester on the car this arrester may be made in the form of a separate device, 45 shown in Fig. 2, in which case the bell 4' has a top closure or head 7, from which projects upwardly the yielding bumpers 8 with which the car would first come in contact in case of accident; the bell being so supported

immediately above the water that the weight 50 of the descending car would immediately release the bell and cause it to come in contact with the water as though it were a unit with the car. 9 represents such a supporting means of sufficiently flimsy character as to 55 yield by pressure above, yet capable of sustaining the safety attachment under ordinary circumstances. The cone 5' also enters into this combination as before.

Preferably the conical deflector 5' has its 60 apex within the plane of the lower edge of the bell so that on striking the water a seal is first formed completely around the cone or pyramid offering a resisting wall to the outward splash of the pyramid or cone. 65 The latter by reason of its wedge shape produces a gentle slowing-up motion which is further assisted by the violent churning of the water inside the bell.

Having thus described my invention what 70 I claim and desire to secure by Letters Patent is—

1. The combination with an elevator cage of a water reservoir in the path of the cage and a safety attachment disposed between 75 the cage and the water reservoir comprising a bell adapted for submergence in the water in the reservoir and a wedge-shape deflector inside the bell and co-acting with the wall thereof to create a churning motion of 80 the water in the bell on the submergence of the latter.

2. In combination with an elevator cage and its well, of a water reservoir in the bottom of the well, a bell dependent from and 85 carried by the cage and adapted for submergence in the water in the well, and a deflector in the bell comprising an inverted cone and adapted to co-act with the bell to cushion the fall of the cage in the event of 90 accident.

In testimony whereof I have hereunto set my hand in the presence of two subscribing witnesses.

ERNEST CLAXTON.
